ADJUSTABLE RECLINING CHAIR

Anton Lorenz, Buffalo, N. Y.

Application January 8, 1944, Serial No. 517,476

13 Claims. (Cl. 155—106)

1

My invention relates to articles of furniture, and more particularly to adjustable reclining chairs or the like, wherein the front portion of the seat is pivoted to a support, the rear portion of the seat is hinged to a back-rest, and a controlling mechanism is provided for an automatic variation in the angle between the back-rest and the seat when the seat is moved from a sitting position into a reclined position and vice versa, so that the back-rest automatically adjusts itself into position to support the back of a person sitting on the chair.

In customary adjustable reclining chairs of above described type the controlling mechanism comprises a guiding link, one end of which is pivoted to the support at a point in a plane below the horizontal plane of the front pivot of the seat, and the other end of which is pivoted to an intermediate point of the back-rest. This arrangement causes a movement of said intermediate point of the back-rest by said guiding link along a circular path during a movement of the seat from the sitting position into the reclined position. While the angles between the back-rest and the seat in the sitting position and in the extreme reclined position may be comfortable, it may be under certain circumstances, that the angles between the back-rest and the seat controlled by said circular path of the intermediate point of the back-rest are not as comfortable as they should be in some of the intermediate positions between the sitting position and the extreme reclined position. Furthermore, this customary arrangement imposes certain limitations on the designer of the chair with respect to the degree of the angle between the back-rest and the seat, with respect to the inclinations of the seat and the back-rest, and with respect to the degree of the variation in the angle between the back-rest and the seat during a movement of the latter.

An object of my invention is to overcome above mentioned disadvantages and to improve upon the adjustable reclining chairs or the like as now ordinarily made.

Another object of my invention is to equip an adjustable reclining chair of above described type with a controlling mechanism, which may be designed in such a manner, that the angles between the back-rest and the seat in intermediate positions of the seat may be freely chosen so as to obtain the utmost of comfort.

A further object of my invention is to arrange adjusting means in an adjustable reclining chair of above described type, by means of which the user of the chair may make a preadjustment of

the angle between the back-rest and the seat and/or a preadjustment of the inclination of the seat or the back-rest.

Still another object of my invention is to equip an adjustable reclining chair of above described type with means, by means of which the user of the chair may determine the degree of variation in the angle between the back-rest and the seat during a swinging movement of the latter.

The above mentioned objects and advantages as well as other objects and advantages will be more fully disclosed in the following specification reference being had to the accompanying drawings forming part of this specification, wherein:

Fig. 1 is a side elevational view of an adjustable reclining chair according to the invention, some parts being broken away.

Fig. 2 is a fragmentary sectional view in an enlarged scale taken on line 2—2 of Fig. 1.

Fig. 3 is a side elevational view of the chair shown in Fig. 1, wherein, however, the cam-like guiding slot of the cam control is brought into a different position relative to the support for a different variation in the angle between the back-rest and the seat during a swinging movement of the latter, and wherein a swingable leg-rest is connected with the back-rest.

Figs. 4 and 4a illustrate several cams with guiding slots of different shapes, which may be used in the cam control for obtaining different movements of the movable members of the chair.

Fig. 5 is a side elevational view of a different embodiment of an adjustable reclining chair, wherein the cam with the guiding slot is rigidly secured to a side wall of the chair, and wherein the extension connected with the cam control is of an adjustable telescopic construction for making the desired preadjustments, some parts being broken away.

Fig. 6 is a side elevational view of an adjustable arm-chair according to the invention, a portion of the side wall being broken away.

Fig. 7 is a fragmentary sectional view in an enlarged scale taken on line 7—7 of Fig. 1.

Fig. 8 is a sectional view in an enlarged scale taken on line 8—8 of Fig. 1.

Fig. 9 is a sectional view in an enlarged scale taken on line 9—9 of Fig. 6, and

Fig. 10 is a sectional view taken on line 10—10 of Fig. 6.

Referring now to Fig. 1, 10 generally indicates a support of any conventional construction. The front portion of a seat 12 is pivoted to the support 10 at 14, and a back-rest 16 is pivoted to the rear portion of the seat at 18. On each side

of the chair an extension or connecting element 20 in the shape of an arm-rest is rigidly connected with the back-rest 16 by screws 22. A cam 24 with a guiding slot 26 of suitable shape is mounted on the support 10. As best shown in Fig. 2, one end of said cam 24 is swingably mounted on a bolt 28 screwed into the support 10. According to Figs. 1 and 7, an element 29 having a threaded bore 31 is rotatably mounted in a bore 33 at the other end of said cam 24. Said threaded bore 31 of the element 29 is engaged with a threaded spindle 30 rotatably and axially immovably mounted in a bore 35 of a member 37 rotatably mounted in a bore 39 of the support 10. Said spindle 30 may be rotated by a handle 32 for adjusting the cam 24 in a predetermined position, for example in the position shown in Fig. 1. A lug 34 projecting from the arm-rest or extension 20 carries a pivot 36 rotatably engaged with a sliding block or sliding element 38 slidably engaged with the actuating surface or guiding slot 26 of the cam 24, as best shown in Fig. 2. The cam control 24, 26, 36, 38 just described may be arranged only on one side or on both sides of the chair.

The sitting position of the seat and back-rest is shown in full lines in Fig. 1. Said sitting position is limited by the upper end of the guiding slot 26 forming an abutment for the sliding block 38 pivotally connected with the lug 34 on the arm-rest 20.

The extreme reclined position 12', 16' of the seat and back-rest is shown in dash and dot lines in Fig. 1. Said extreme reclined position is limited by the bracing member 40 of the support 10, which forms an abutment for the seat.

During a movement of the seat 12 from said sitting position into said reclined position 12', the pivotal connection 36 of the arm-rest or extension 20 with the sliding block 38 of the cam control is guided by the guiding slot 26 of the cam 24, whereby the movement of the back-rest 16 is controlled with the result of an increase in the angle between the back-rest and the seat.

A torsional spring 42 arranged around the pivot 14 has its ends connected with the support 10 and the seat 12 for urging the seat and back-rest from a reclined position into the sitting position limited by the upper end of the guiding slot as described above. Said spring arrangement yieldingly opposing a movement of the members of the chair into a reclined position may be of any desired construction, for example of a construction as shown in my U. S. Patent 2,365,200 relating to "An adjustable reclining chair" issued December 19, 1944. Furthermore, it may be mentioned that resilient means for returning the seat and back-rest into the sitting position may be arranged at points other than the pivot 14. If the user of the chair wishes to relax and leans his body against the back-rest 16, the back-rest and the seat are moved against the action of such resilient means into a reclined position.

The movable members 12, 16, 20 of the chair may be held in any desired position by means of a locking device generally indicated by 44. According to Figs. 1 and 8, said locking device 44 comprises a handle 45 screwed on the threaded end of the pivot 18 between the seat 12 and the element 47 rigidly secured to the backrest 16. Said pivot 18 has a square portion 49 engaged with a square aperture of the seat 12, whereby the pivot is prevented from rotation. A head 51 of the pivot 18 rests against a surface of the seat 12. When the user of the chair loosens the

locking handle 45, the surface of the hub 53 of said handle is disengaged from the surface of the element 47, so that the movable members of the chair may be freely moved from one position into another one. When the locking handle 45 is tightened, the surface of the hub of the handle is pressed against the element 47, whereby the latter is pressed against the seat 12 engaged with the head 51 of the pivot 18, so that the movable members of the chair are held in their position. Of course, the locking means may be of different type and may be arranged at another part of the chair, if desired.

As pointed out above, the position of the cam control relative to the support may be adjusted by means of the spindle 30, 32 controlling the position of the cam 24 swingably mounted on a pivot of the support. For example, the cam 24 may be brought from the position shown in Fig. 1 into the position shown in Fig. 3. This adjustment causes no change in the angle between the back-rest 16 and the seat 12 in the sitting position, as the axes of the pivots 28 and 36 (Fig. 2) are in alignment with each other in said sitting position. However, the angle between the back-rest and the seat in the reclined position 12', 16' of Fig. 3 becomes larger than the corresponding angle between the back-rest and the seat in the reclined position 12', 16' according to Fig. 1. As will be readily understood, an adjustment of the cam control by swinging the cam 24 about its pivot 28 may also cause changes in the inclinations of the seat and back-rest, if the axes of the pivots 28 and 36 do not coincide in the sitting position of the seat.

As a matter of example, the chair shown in Fig. 3 being otherwise the same chair as that shown in Fig. 1, is equipped with a leg-rest 46 swingably mounted on the support 10 at 48. One end of a connecting link 50 is pivotally connected with an extension 52 of the leg-rest at 54, while the other end of said connecting link is pivoted to the back-rest 16 at 56. Said connecting mechanism serves to swing the leg-rest 46 simultaneously with a swinging movement of the seat 12.

According to the embodiment shown in Figs. 1-3, the adjustments of the inclinations of the seat and back-rest and of the relative movements thereof are obtained by an adjustable cam 24 movably mounted on the support 10. Instead of such a single movable and adjustable cam, however, a set of cams with guiding slots of different shape may be used for obtaining adjustments of this type. In such a case means, for example screws, are provided for a detachable stationary mounting of the selected cam of said set of cams on the support of the chair, so that a certain cam may be readily replaced by another cam of the set.

Figs. 4 and 4a illustrate as a matter of example several cams of such a set of cams with guiding slots of different shape and direction. If a cam 24a with a straight horizontal actuating surface or guiding slot is attached to the support 10 of the chair by means of screws 25 passing through holes of the cam as shown in Fig. 4 and the user of the chair leans his body against the back-rest, the back-rest swings about the pivot on the rear portion of the seat, while the seat remains substantially in the horizontal position or may be even slightly lifted. If a cam 24b with a straight vertical actuating surface or guiding slot shown in Fig. 4a is arranged on the support of the chair, the seat may be swung about its front pivot, while the inclination of the back-rest remains substan-

tially unchanged. If a cam 24c with a straight guiding slot extending toward the pivot between the back-rest and seat is arranged on the support of the chair, the seat and the back-rest are swung through approximately equal angles. Cams with straight guiding slots extending between the guiding slots of the cam 24a and cam 24c cause a greater change in the inclination of the back-rest than in the inclination of the seat, or in other words the angular movement of the back-rest is faster than that of the seat, while cams with straight slots extending between the guiding slots of the cam 24b and 24c cause a greater change in the inclination of the seat than in the inclination of the back-rest, i.e., in such a case the angular movement of the seat is faster than that of the back-rest. If a cam 24d or 24e with a curved actuating surface or guiding slot is used, a mixture of fast and slow angular movements of the seat and back-rest is obtained. For example, the cam 24d causes at the beginning of the curved guiding slot a faster angular movement of the back-rest, after which the angular movement of the seat is accelerated and the angular movement of the back-rest is retarded; in any case, however, the back-rest is swung through a greater angle than the seat, as the curved guiding slot of the cam 24d is between the guiding slots of the cams 24a and 24c. On the other hand, the cam 24e causes at the beginning of the curved guiding slot a faster angular movement of the seat, after which the angular movement of the back-rest is accelerated and the angular movement of the seat is retarded; in this case, however, the seat is swung through a greater angle than the back-rest, as the curved guiding slot of the cam 24e is between the guiding slots of the cams 24b and 24c.

According to the embodiment of a chair shown in Fig. 5, the center portion of a supporting member 58 is carried by a spindle 64 screwed into a conventional pedestal 66. The side walls 60 including the arm-rests 62 are held by two pairs of arms 59 which project from the front end and rear end of the center portion of the supporting member 58. The front portion of the seat 12 is pivoted at 14 to a third arm 61 projecting from the front end of the center portion of the supporting member 58 and the back-rest is pivoted to the rear portion of the seat at 18. The seat 12 is under the action of a resilient wire or spring 68 arranged between the supporting member 58 and the lower surface of the seat. According to Fig. 5, the cam 124 having a curved guiding slot 126 is immovably mounted on the side wall 60 by means of screws 70. In order to make adjustments of above described type, the extension or connecting element 120 is of a telescopic construction, and its length may be adjusted by means of an adjusting screw 72. One end of the extension 120, which, in this embodiment, does not form an arm-rest, is rigidly secured to the back-rest 16 by screws. The other end of the telescopic extension carries the lug 134 pivotally connected at 36 with the sliding block engaged with the guiding slot 126 of the cam 124. When the user of the chair leans his body against the back-rest 16, the sitting arrangement 12, 16 is moved against the action of the spring 68 from the sitting position shown in full lines through intermediate reclining positions, such as the position 12'', 16'', into the extreme reclined position 12', 16' limited by the engagement of the sliding block of the cam control with the lower end of the guiding slot 126. During this

movement of the movable parts of the chair the angle between the back-rest and the seat is automatically controlled by the cam control acting on the extension 120 projecting from the back-rest, whereby said angle is increased. As will be readily understood, different inclinations of the seat and back-rest are obtained, when the length of the telescopic extension 120 is shortened or lengthened.

Fig. 6 illustrates an arm-chair; wherein the seat 12 is pivoted to the frame or support 74 at 14 and the back-rest 16 is hinged to the rear portion of the seat at 18. The arm-rests are formed by the upper portion 76 of the frame 74. The seat 12 is under the action of an S-shaped spring 78 having its ends secured to the bottom of the frame 74 and to the seat 12 respectively. The spring serves to return the sitting arrangement 12, 16 from a reclined position into its sitting position and to limit said sitting position.

The cam 224 with a straight guiding slot 226 is rigidly secured to the frame 74 by screws 80. In contrast to the embodiments shown in Figs. 1-5, according to Fig. 6 the sliding block 238 slidably engaged with the guiding slot 226 is rigidly connected with one end of the connecting element 220 by screws 82, and the other end of said connecting element 220 is pivotally connected with the back-rest at 84. When the sitting arrangement 12, 16 is moved from the sitting position into the reclined position 12', 16', the angle between the back-rest and the seat is automatically increased by the cam control 224, 226, 238.

The chair according to Fig. 6 is provided with a locking device 86 comprising a rod 88 pivoted to the seat 12 at 90 and engaged by a clamping sleeve 92. As best shown in Fig. 9, said clamping sleeve may be tightened on the rod 88 by means of an adjusting knob 96 threaded on the threaded end of a bolt 97 for locking the movable members 12, 16, 220 of the chair in any adjusted position. A head 94 of the bolt 97 passing through registering openings of the clamping sleeve 92 and a member 99 of the frame rests against the clamping sleeve, and the adjusting knob 96 rests against said member 99.

Furthermore, a limiting stop generally indicated by 98 is adjustably mounted on the cam 224 for limiting the stroke of the sliding block 238 so as to limit the extreme reclined position 12', 16' of the seat and back-rest. Obviously, said extreme reclined position may be varied by a change in the position of the limiting stop 98 in the guiding slot 226. As best shown in Fig. 10, said adjustable limiting stop 98 comprises a head screw 101 inserted into the guiding slot 226 for cooperation of its portion 103 with a sliding block 238 and screwed into a threaded bore 105 of a plate 107 resting on the cam 224.

Fig. 6 shows means for adjusting the position of the cam or for adjusting the length of the extension or for replacing a cam by another cam of different shape for adjusting the inclinations of the seat and back-rest and the relative positions thereof, but it is understood that any of such adjusting means as shown in Figs. 1-5 either alone or in combination with each other may be applied to a chair as shown in Fig. 6 so as to render same adjustable in that respect.

I have described preferred embodiments of my invention, but it is clear that numerous changes and omissions may be made without departing from the spirit of my invention. For example different types of cams and sliding elements cooperating with said cams may be used, or the swing-

able arrangement of the adjustable cams shown in the drawings may be replaced by a slideable arrangement of such cams in guides. Furthermore, different inclinations of the seat and back-rest may be obtained by arranging extensions of different lengths on the back-rest and/or by arranging the extensions in a different manner at different points on the back-rest. Moreover, the normal sitting position must not necessarily be a horizontal position as shown in the drawings; if desired, the seat may be slightly rearwardly inclined in the normal sitting position.

My invention may be applied to many types of chairs, for example desk-chairs, arm chairs, reclining chairs for the household, garden-chairs, chairs for use in railroad cars, chairs for use in airplanes, etc. Furthermore, my invention may be applied to other articles of furniture, such as sofas or the like.

What I claim is:

1. An adjustable reclining chair or the like comprising: a support, a seat, a back-rest, the front portion of said seat being pivoted to said support, the back-rest being pivoted to the rear portion of said seat, said seat being swingable about its front pivot from a sitting position into a reclined position, a connecting element, one end of said connecting element being connected with said back-rest intermediate the top and bottom thereof, said connecting element projecting laterally at a side of said back-rest, cam control means mounted on the support and connected with a portion of said connecting element laterally remote from said connection between the connecting element and the back-rest, one of said two connections of said connecting element being a pivotal connection, the other connection of said connecting element being a rigid connection, and resilient means arranged between the support and a movable member of the chair for yieldingly opposing a movement of the movable members into the reclined position.

2. An adjustable reclining chair or the like comprising: a support, a seat, a back-rest, the front portion of said seat being pivoted to said support, the back-rest being pivoted to the rear portion of said seat, said seat being swingable about its front pivot from a sitting position into a reclined position, a connecting element, one end of said connecting element being connected with said back-rest intermediate the top and bottom thereof, said connecting element projecting laterally at a side of said back-rest, cam control means mounted on the support and connected with a portion of said connecting element laterally remote from said connection between the connecting element and the back-rest, one of said two connections of said connecting element being a pivotal connection, the other connection of said connecting element being a rigid connection, adjustable means for varying the position of said cam control means relative to said support, and resilient means arranged between the support and a movable member of the chair for yieldingly opposing a movement of the movable members into the reclined position.

3. In combination with an adjustable reclining chair or the like as claimed in claim 1, said cam control means including a cam movably mounted on the support and a sliding element engaged with said cam and connected with said portion of the connecting element laterally remote from the connection of the connecting element with the back-rest, and adjusting means con-

nected with said cam and said support for adjusting said cam in a predetermined position.

4. An adjustable reclining chair or the like comprising: a support, a seat, a back-rest, the front portion of said seat being pivoted to said support, the back-rest being pivoted to the rear portion of said seat, said seat being swingable about its front pivot from a sitting position into a reclined position, a connecting element of variable length, means for holding the sections thereof to provide a predetermined length, one end of said connecting element being connected with said back-rest intermediate the top and bottom thereof, said connecting element projecting laterally at a side of said back-rest, cam control means mounted on the support and connected with a portion of said connecting element laterally remote from said connection between the connecting element and the back-rest, one of said two connections of said connecting element being a pivotal connection, the other connection of said connecting element being a rigid connection, and resilient means arranged between the support and a movable member of the chair for yieldingly opposing a movement of the movable members into the reclined position.

5. In an adjustable reclining chair or the like as claimed in claim 1, said cam control means including a cam with a straight actuating surface and a sliding element engaged with said straight actuating surface of said cam and connected with said portion of the connecting element laterally remote from the connection of the connecting element with the back-rest.

6. In an adjustable reclining chair or the like as claimed in claim 1, said cam control means including a cam with a curved actuating surface and a sliding element engaged with said curved actuating surface of said cam and connected with said portion of the connecting element laterally remote from the connection of the connecting element with the back-rest.

7. In an adjustable reclining chair or the like as claimed in claim 1, said connecting element extending substantially horizontally so as to form an arm-rest of the chair.

8. In combination with an adjustable reclining chair or the like as claimed in claim 1, a leg-rest swingably mounted on said support, and connecting means connecting a movable member of the chair with said swingable leg-rest for moving same.

9. An adjustable reclining chair or the like as claimed in claim 1, including limiting means arranged for cooperation with a movable member of the chair so as to limit an extreme position of the movable members of the chair.

10. In an adjustable reclining chair or the like as claimed in claim 1, said cam control means including a cam with an actuating surface and a sliding element engaged with said actuating surface and connected with said portion of the connecting element laterally remote from the connection of the connecting element with the back-rest, and an adjustable limiting means arranged on said cam control means for limiting the stroke of said sliding element so as to limit an extreme position of the movable members of the chair.

11. An adjustable reclining chair or the like as claimed in claim 1 including locking means arranged for cooperation with two members of the chair which are movable relative to each other so as to lock the movable members of the chair in an adjusted position.

12. An adjustable reclining chair or the like

comprising: a support, a seat, a back-rest, the front portion of said seat being pivoted to said support, the back-rest being pivoted to the rear portion of said seat, said seat being swingable about its front pivot from a sitting position into a reclined position, an extension rigidly connected with said back-rest, said extension projecting laterally at a side of the back-rest intermediate the top and bottom thereof, cam control means mounted on the support and pivotally connected with a laterally projecting portion of said extension, and resilient means arranged between the support and a movable member of the chair for yieldingly opposing a movement of the movable members into the reclined position.

13. An adjustable reclining chair or the like comprising: a support, a seat, a back-rest, the front portion of said seat being pivoted to said support, the back-rest being pivoted to the rear portion of said seat, said seat being swingable about its front pivot from a sitting position into a reclined position, a connecting element, one end of said connecting element being pivotally connected with said back-rest intermediate the top and bottom thereof, said connecting element projecting laterally at a side of said back-rest, a cam with an actuating surface mounted on the support, a sliding element engaged with said actuating

ing surface and rigidly connected with a portion of said connecting element laterally remote from said pivotal connection between the connecting element and the back-rest, and resilient means arranged between the support and a movable member of the chair for yieldingly opposing a movement of the movable members into the reclined position.
